UNITED STATES PATENT OFFICE

158,578

COMBINED PURSE AND RADIO

Horace Albert James, Riverton, N. J.

Application May 16, 1949, Serial No. 2,701

Term of patent 7 years

(Cl. D87—3)

To all whom it may concern:

Be it known that I, Horace Albert James, a citizen of the United States of America, residing at Riverton, in the county of Burlington and State of New Jersey, have invented a new, original, and ornamental Design for a Combined Purse and Radio, of which the following is a specification, reference being had to the accompanying drawing, forming a part thereof.

In the drawing:

Figure 1 is a front perspective view of a combined purse and radio embodying my new design illustrating the radio compartment in an open position; and

Figure 2 is an end elevational view thereof with the radio compartment closed.

The opposite end of the combined purse and radio is the same as that shown in Figures 1 and 2 while the back thereof is plain.

I claim:

The ornamental design for a combined purse and radio as shown and described.

HORACE ALBERT JAMES.
